LUBRICATOR, FILTER AND REGULATOR UNIT

Robert E. Becker, Logansport, Ind., assignor to Logansport Machine Company, Inc., a corporation of Indiana

Application February 14, 1956, Serial No. 40,164

Term of patent 14 years

(Cl. D52—1)

Des. 179,112

PAGE 2

Fig. 2

Fig. 3

Fig. 4

Figure 1 is a front elevational view of a lubricator, filter and regulator unit showing my new design;

Figure 2 is a side elevational view thereof;

Figure 3 is a top plan view; and

Figure 4 is a side elevational view of the opposite side from Figure 2.

I claim:

The ornamental design for a lubricator, filter and regulator unit, as shown.
